(57) **CLAIM**

The ornamental design for a paraffin bath, as shown and described.

DESCRIPTION

FIG. 1 is a perspective view of our new design; FIG. 2 is a front elevation view of our new design; FIG. 3 is a left side elevation view of our new design; FIG. 4 is a right side elevation view of our new design; FIG. 5 is a rear elevation view of our new design; FIG. 6 is a top plan view of our new design; and, FIG. 7 is a bottom plan view of our new design. The design is of a paraffin bath having a slanted top. The broken lines in FIGS. 2-5 and 7 are for illustrative purposes only and form no part of the claimed design.
